John W. Doty Inventor
By C. Snow & Co. Attorneys

UNITED STATES PATENT OFFICE.

JOHN W. DOTY, OF OLNEY, ILLINOIS.

MOP-HANDLE FASTENER.

Application filed August 20, 1926. Serial No. 130,512.

The present invention has reference to mop head constructions, and more particularly to the construction of mop heads especially designed for use in mopping highly polished floors.

The primary object of the invention is to provide novel means for adjustably connecting the mop handle to the head, so that the handle may be moved to various angles with respect to the head, permitting the mopping surface of the head to be reversed without the necessity of removing the head from the handle.

With the foregoing and other objects in view which will appear as the description proceeds, the invention resides in the combination and arrangement of parts and in the details of construction hereinafter described and claimed it being understood that changes in the precise embodiment of the invention herein disclosed, may be made within the scope of what is claimed, without departing from the spirit of the invention.

Referring to the drawing:

Figure 1 is a plan view of a mop constructed in accordance with the invention.

Figure 2 is a vertical sectional view through the head connecting means.

Figure 3 is a sectional view taken on line 3-3 of Figure 2.

Referring to the drawing in detail, the connecting member employed for connecting the head and handle, includes a socket member 5 in which the handle 6 is positioned, the socket member including a pair of spaced arms 7 diverging towards their outer ends, where they are provided with openings for the reception of the bolt 8.

The reference character 9 indicates one of the clamping jaws of the connecting device and includes a length of heavy metal bent intermediate its side edges as clearly shown by Figure 3. At the ends of the jaw 9 are caps 10 which have inwardly extended flanges embracing portions of the jaw 9 to secure the members 10 to the jaw 9.

The caps 10 are also formed with openings designed to register with the openings in the arms 7 and receive the bolt 8 in a manner as clearly shown by the drawing.

Mounted on the threaded end of the bolt 8 is a nut 11 which is adapted to cooperate with the head 12 of the bolt in clamping the caps 10 to the jaw 9.

An opening is formed in the jaw 9 at a point intermediate its ends and accommodates bolt 13 which also extends through the substantially long clamping jaw 14 adapted to cooperate with the jaw 9 in securing the wire brush frame 15 to the connecting device.

This brush frame 15 includes a wire member its ends bent at right angles as at 16, where they pass through openings of the jaw 9, so that the ends of the frame 15 will be securely held against movement. A nut indicated at 17 is positioned on the bolt 13 and is adapted to cooperate with the head of the bolt in drawing the members 9 and 14 together into clamping relation with the member 15.

As illustrated by Figure 3, the widths of the arms 7 are less than the distance between the side edges of the frame 9 with the result that the arms 7 may be swung to positions as shown in dotted lines in Figure 3, or from one side of the frame 9 to the other. Thus it will be seen that due to this construction a free swinging movement of the handle with respect to the brush head may be had at all times, and that the brush head may be reversed on the surface being mopped and the handle still be supported at an angle convenient for operation.

It will further be noted that due to this construction, the reversing of the brush head to change the mopping surface may be accomplished without the necessity of removing the head to reverse the same.

I claim:

1. In a mop, a head including a wire frame, a handle, a socket member in which the handle is positioned, said socket member having arms extending therefrom, a clamp including jaws adapted to embrace portions of the wire frame, strands carried by the frame, and means for connecting the arms of the socket member to the clamp to permit the socket member to move to various angles with respect to the mop head.

2. In a mop, a head including a frame embodying a length of wire having right angled ends, a clamp embodying jaws and having openings to receive the right angled ends, means for moving the clamp into close engagement with the frame, a socket member to receive one end of a handle, and means

for connecting the socket member to the clamp to permit the socket member to move to various angles with respect to the head

10

In testimony that I claim the foregoing as my own, I have hereto affixed my signature.

JOHN W. DOTY.
